UNITED STATES PATENT OFFICE.

WILLIAM H. FOX, OF HOLLYWOOD, CALIFORNIA.

WATER-VAPORIZER FOR INTERNAL-COMBUSTION ENGINES.

1,239,380.

Specification of Letters Patent.

Patented Sept. 4, 1917.

Application filed March 12, 1917. Serial No. 184,237.

To all whom it may concern:

Be it known that I, WILLIAM H. FOX, a citizen of the United States, residing at Hollywood, in the county of Los Angeles and State of California, have invented new and useful Improvements in Water-Vaporizers for Internal-Combustion Engines, of which the following is a specification.

This invention relates to a vaporizer and particularly pertains to a device adapted to supply aqueous vapor to the gaseous fuel delivered to an internal combustion engine. It has been found by experiment that an internal combustion engine will operate in a more efficient manner when a proportion of aqueous vapor has been added to the gaseous fuel exploded within its cylinders. It is an object of this invention to provide simple means for delivering such a vapor to the intake manifold of the engine and insuring that it will be injected into the fuel mixture passing from the carburetor.

Another object of this invention is to provide simple means for preventing the overflow of the device and the objectionable results attendant thereto.

It is a further object of this invention to provide a vaporizer which is simple in its construction, possesses no movable parts, and is not liable to become inoperative.

Other objects will appear hereinafter.

The invention is illustrated, by way of example, in the accompanying drawings in which:

Figure 1 is a fragmentary view of the forward end of a motor vehicle with parts broken away to disclose the operative position of the vaporizer in relation to the engine and its manifold.

Fig. 2 is an enlarged view of the vaporizer disassociated from its operative position upon an engine and with parts broken away to illustrate the interior construction of the vaporizing chamber.

Referring more particularly to the drawings, 10 indicates an internal combustion engine which is here shown as mounted upon the frame of a motor vehicle. The engine is adapted to be cooled by the water which circulates through a radiator 11 at the front of the vehicle. The cylinders of the engine are supplied with a gaseous fuel formed within a carburetor 12 and delivered to the engine through a manifold 13. It will be understood that all of the foregoing parts are of stock design and that the present in-

vention relates to a vaporizer 14 adapted to be used in connection with the carburetor.

The vaporizer is formed with a water reservoir 15 which extends horizontally at the bottom of the structure and supports a conical vaporizing chamber 16 which is secured upon the top of the reservoir. A horizontal partition wall or secondary floor 17 is placed between the top of the reservoir and the lower opened end of the vaporizing chamber. Communication is had between the reservoir and chamber by means of an opening 18 formed through the partition. Mounted upon the plate 17 and at one side of the vaporizing chamber is an overflow compartment 19 to which a surplus of water from the reservoir may overflow through an opening 20 in the partition wall 17 and be carried out through a drain pipe 21 in the side of the compartment. The reservoir is supplied with water and vapor by a tube 22 which leads directly to a point within the radiator cap 23. As the water within the radiator boils up it will overflow into the tube and be drained into the reservoir 15 of the vaporizer. Vapor which forms within the radiator will also pass downwardly through this tube even though the radiator has not boiled sufficiently to cause water to rise to the level of the opening of the tube. The end of the radiator drain tube 22 is secured within the vaporizer preferably at one side of the opening 18. Mounted upon the opposite side of the vaporizer and extending upwardly therefrom is a vent tube 24. This tube extends downwardly into the vaporizing chamber and has an upper overturned end which acts as a trap for foreign substance and permits air to pass into the reservoir under favorable conditions.

Communication is established between the vaporizing chamber 16 and the manifold 13 by means of a conduit 25. This conduit is secured at one end within the apex of the vaporizing chamber and at the other end by a plug 26 within the neck of the manifold 13. A considerable length of this conduit is wrapped around the exhaust manifold 27 of the engine so that the vapor passing from the vaporizer to the intake manifold will be superheated prior to its injection into the manifold.

In operation, the engine is set in motion and will produce a suction through the intake manifold and the carburetor 12. The vaporizer will also be influenced by the suc-

tion of the engine and will cause air to be drawn in through the vent pipe 24 to the chamber 16 of the vaporizer and then up through the water in the vaporizing chamber. 5 As the air is drawn up it will carry water with it. This water and air will vaporize within the conical vaporizing chamber and will then be drawn through the pipe 25 around the exhaust manifold and to the intake manifold, where it will enter through the upturned nozzle 28. It will be understood that the water within the reservoir 15 has previously been drained from the top of the radiator 11 and that this water, after the car 10 has become heated, will be of a high temperature. It may also be possible that steam will pass through the pipe 22 and to the reservoir. In both cases, the heat of the liquid will improve the results attained as 15 when the water and air are drawn into the vaporizer they will be more thoroughly vaporized. This vaporization will be improved by the heating action of the exhaust manifold. In case the water from the radiator 20 drains into the reservoir 15 at a higher rate of speed than it is drawn to the engine, it will overflow into compartment 19 and be drawn away through the drain tube 21. In order that the volume of aqueous vapor 25 passing to the intake manifold is in proper proportion to the engine requirements, a regulating valve 29 is mounted at the end of the vaporizing chamber and adapted to regulate the flow of vapor therefrom. 30 35 While I have shown the preferred construction of my vaporizer as now known to me, it will be understood that various changes in the combination, construction and arrangement of parts may be made by those skilled in the art without departing from the spirit of my invention.

I claim:

1. A vaporizer, comprising a water reservoir, a vaporizing chamber mounted in connection therewith, means whereby said chamber will connect with the intake manifold of an internal combustion engine, means whereby the suction of the engine will act to create a vapor within said vaporizing chamber and draw it into the intake manifold in combination with a gaseous fuel passing therethrough, means whereby water and vapor may be delivered to said reservoir from the radiator of said engine, and means 45 whereby the aqueous vapor drawn from the 50 vaporizing chamber to the intake manifold will be heated as it is delivered thereto. 55

vaporizing chamber to the intake manifold will be heated as it is delivered thereto.

2. A vaporizer, comprising a water reservoir, a vaporizing chamber mounted in connection therewith, means whereby said chamber will connect with the intake manifold of an internal combustion engine, means whereby the suction of the engine will act to create a vapor within said vaporizing chamber and draw it into the intake manifold in combination with a gaseous fuel passing therethrough, means whereby water and vapor may be delivered to said reservoir from the radiator of said engine, means whereby the aqueous vapor drawn from the vaporizing chamber to the intake manifold will be heated as it is delivered thereto, and overflow means for regulating the quantity of water and vapor within said reservoir. 60 65 70

3. A vaporizer, comprising a water reservoir, a vaporizing chamber mounted in connection therewith, means whereby said chamber will connect with the intake manifold of an internal combustion engine, means whereby the suction of the engine will act to create a vapor within said vaporizing chamber and draw it into the intake manifold in combination with a gaseous fuel passing therethrough, means whereby water and vapor may be delivered to said reservoir from the radiator of said engine, means whereby the aqueous vapor drawn from the vaporizing chamber to the intake manifold will be heated as it is delivered thereto, overflow means for regulating the quantity of water and vapor within said reservoir from 75 80 85 90 95

means for controlling the volume of aqueous vapor uniting with the gaseous fuel within said intake manifold.

4. In a vaporizer for internal combustion engines, a reservoir, a conical vaporizing chamber extending upwardly from the reservoir, a secondary floor between the reservoir and the chamber and having an opening, an over-flow compartment connected to the reservoir, a tube discharging downwardly into the side of the vaporizing chamber, a vent tube mounted upon the opposite side of the vaporizing chamber and extending from near the secondary floor upwardly 100 and outwardly, and a conduit leading from the apex of the vaporizing chamber. 105

In testimony whereof I have signed my name to this specification.

WILLIAM H. FOX.
